UNITED STATES PATENT OFFICE.

WILLARD N. SAWYER, OF WINCHENDON, MASSACHUSETTS, ASSIGNOR TO WILLIAM M. WHITNEY, OF WINCHENDON, MASSACHUSETTS.

WOOD-PLANING MACHINE.

1,302,717.

Specification of Letters Patent.

Patented May 6, 1919.

Application filed December 3, 1917. Serial No. 205,039.

To all whom it may concern:

Be it known that I, WILLARD N. SAWYER, a citizen of the United States, residing in Winchendon, county of Worcester, and State of Massachusetts, have invented an Improvement in Wood-Planing Machines, of which the following description, in connection with the accompanying drawings, is a specification, like characters on the drawings representing like parts.

The invention hereinafter described relates to wood planing machines and the like. It is customary to provide machines of this character with sets of rolls for feeding the work through the machine past a cutter. One roll of a set should be pressed yieldingly toward its companion roll in order that the rolls may conform to work of varying thickness and exert sufficient pressure thereon to grip and feed the same through the machine.

It is necessary to adjust the journal boxes of the lower rolls from time to time to vary the elevation of said rolls and their relation to the upper rolls; and it is also desirable to vary the tension of the springs which act on the rolls in order to vary the pressure thereof on the work. Heretofore, these adjustments have been difficult to make, owing to the inaccessibility of the adjusting parts.

The present invention, among other objects, aims to provide a simple, readily accessible means whereby the aforesaid adjustments may be conveniently and easily made.

The character of the invention may be best understood by reference to the following description of one good form of the invention shown in the accompanying drawing, wherein:

Figure 1 is a side elevation of a portion of a wood planing machine having rolls provided with devices embodying the invention; and

Fig. 2 on an enlarged scale is a view showing said devices in vertical section.

Referring to the drawing, the machine shown therein comprises a frame 1 having the usual rotary cutter 3 mounted thereon and a bridge 5 opposed thereto for guiding and holding the work down to said cutter. To feed the work past the cutter, a set of upper and lower in-feed rolls 7 and 9 and a set of upper and lower out-feed rolls 11 and 13 are provided.

Roll controlling devices embodying the invention are shown herein as applied to the ends of the lower out-feed roll. Since the devices for both ends of the roll are similar, a description of one will suffice for both.

Referring more particularly to Fig. 2, the lower out-feed roll 13 is provided with a shaft 15 having an end journaled in a bearing box 17 adapted to slide vertically in a guideway 19 in the machine frame.

To support the box a vertical post 23 is provided projecting through an opening in the machine frame and having its lower end portion 25 threaded in a bore in said frame. A portion 27 of this post intermediate its ends may be slabbed off to receive a wrench which may conveniently be presented to said post through said opening. The post may be secured in different positions of vertical adjustment by a lock nut 29 adapted to bear on an edge of the frame above said bore.

A collar 31 loose on said post may be adjusted up or down by an adjusting nut 33 secured by a lock nut 35.

To yieldingly support the bearing box, a coil spring 37 is provided encircling said post and confined between said lower collar 31 and an upper collar 39 upon which the box rests.

To limit upward movement of said box, by said spring, suitable stop means may be provided, in the present instance of the invention, in the form of an internal flange 41 on said collar adapted to engage the under edge of a head 43 on said post.

There is, however, a space between the top of said head and the bottom of said box sufficient to permit the box to move downward somewhat against the resistance of said spring when work is passing between the rolls.

The tension of the spring may be readily increased without changing the elevation of the bearing box. To accomplish this the collar 31 is moved upward by the adjusting nut 33.

The head of the supporting post co-operates desirably with the upper collar to limit expansion of the spring. It will be noted that the top of the head is spaced from the top of the upper collar when the latter is pressed to its limit by the spring. As a result, when the box is pressed downward, it can contract the spring until the box is limited by its engagement with the head of the

post. If the post should be adjusted so that the top of its head is beneath the bottom of the guideway for the box, the downward movement of the box will be limited by its engagement with the top of said head.

It will be noted that the screw and nut for controlling the elevation of the journal box, and the screws for controlling the tension of the spring, are all located in large openings at opposed sides of the machine, where they are unobstructed by parts of the machine and are readily accessible for adjustment as desired.

The term "cutter" appearing in certain of the claims is not to be understood as limited to a rotary cutter, but rather as generic to a scraper or other tool for treating the work.

It will be understood that the invention is not limited to the specific embodiment shown herein, but that extensive deviations may be made therefrom without departing from the spirit and scope of the appended claims.

What is claimed is:

- 25 1. In a machine of the character described, the combination with a frame, of a cutter mounted thereon, means for feeding work relatively to the cutter including upper and lower feed rolls, shafts for said rolls, bearing boxes for the shaft for the lower roll, guides on said frame for said boxes, and supporting means for said boxes, each including a spring, means to adjust said support to vary the elevation of the box, and means to vary the tension of said spring without varying the elevation of said box.
- 30 2. In a machine of the character described, the combination with upper and lower rolls, of a bearing box for the lower roll, and means yieldingly to support said box comprising a post, a member movable on said post and serving as a rest for the box, a coil spring on said post to yieldingly support said movable member, and means to

vary the tension of said spring without varying the elevation of said box. 45

3. In a machine of the character described, the combination with upper and lower rolls, of bearing boxes for the lower roll, and devices yieldingly to support said boxes, each comprising a post, a stop on said post, upper and lower collars, one slideable and the other adjustable to different fixed positions on said post, spring means confined between said collars and tending to urge the upper collar 50 toward said stop, and means bodily to vary the elevation of said post and the parts carried thereby without disturbing the tension of said spring means. 55

4. In a machine of the character described, the combination with an upright frame having an opening therein, of a guide on said frame above said opening, a bearing box slideable in said guide, a post extending across said opening toward said box and 60 having means adjustably securing its lower end on said frame at the bottom of said opening, a pair of members on said post, one being movable and supporting the box and the other having means for adjusting 65 the same to different fixed positions, and a coil spring confined between said members to yieldingly sustain the movable member, access to both of said adjusting means being had through said opening. 75

5. In a machine of the character described, the combination of upper and lower feed rolls, of bearing boxes for said rolls, and devices yieldingly to sustain said boxes, each comprising a supporting member, a spring 80 thereon, adjustable means to vary the elevation of said supporting member, and adjustable means to vary the tension of said spring without varying the elevation of said supporting member. 85

In testimony whereof, I have signed my name to this specification.

WILLARD N. SAWYER.
